GUIDO FORNACA, OF TURIN, ITALY.

VALVE MECHANISM FOR INTERNAL-COMBUSTION ENGINES.

1,096,900.

Specification of Letters Patent.

Patented May 19, 1914.

Application filed December 17, 1912. Serial No. 737,173.

To all whom it may concern:

Be it known that I, GUIDO FORNACA, a subject of the King of Italy, residing at Turin, Italy, have invented certain new and useful Improvements in Valve Mechanism for Internal-Combustion Engines, of which the following is a full, clear, and exact specification.

This invention relates to internal combustion engines and more particularly has reference to means for varying the extent of opening of a valve, according to the power desired to be developed by the engine.

As specifically shown herein, the extent of opening of a valve may be varied without varying the time of opening and closing the valve in the cycle of operation of the engine, it being seen that the farther the valve is opened the greater the charge of gas which can be admitted or discharged from the engine, such as air, combustible mixture, liquid fuel, exhaust gases, etc. Thereby, it is possible to obtain a very effective regulation of an internal combustion engine by the increased range of valve control afforded by this invention, and without affecting the predetermined timing of the various parts of the cycle.

The invention is applicable to either two cycle, four cycle or other types of engines, in connection with valves of various types, and is specifically shown herein applied to a two cycle engine of the Diesel type, though it will be understood that the invention is not restricted to engines of this type or cycle, or to puppet valves, which are illustrated herein for purposes of convenience.

In carrying out the invention I prefer to operate the valves from an oscillating shaft, and the invention is especially concerned with connections for manually varying the angle of oscillation of the shaft either during the operation of the engine or while the engine is at rest, and also permitting a governor to automatically vary the angle of oscillation of the shaft while the engine is running in accordance with the speed. The greater the angle of oscillation of the shaft the wider the valve will be opened, and vice versa, without varying the instant of opening or closing.

The invention will be more fully understood in connection with the description of the accompanying drawings, wherein—

55 Figure 1 is a vertical section of a two-cycle

Diesel engine taken through the valve for admitting air for scavenging the cylinder; Fig. 2 is a vertical section taken through the center of the fuel valve with parts of the latter omitted; Fig. 3 is a detail on an enlarged scale illustrating the movements of the oscillating shaft for controlling a valve; Fig. 4 is a diagram illustrating the variations effected by adjustment; Fig. 5 shows a slight modification of the adjusting means, 65 and Fig. 6 is a detail showing means for controlling a valve automatically by a governor.

The two cycle engine indicated in Figs. 1 and 2, representing in general the Diesel or similar high speed type, comprises a base 1 carrying the cylinder 2. 3 is the piston, 4 the exhaust port controlled by the piston 3, which latter drives the engine shaft through the connecting rod 5. It will be understood that suitable cooling means, 6, of any approved construction or arrangement will be provided. The air valve chamber 7 is shown provided with a valve head 8 connected to the stem 9, the exterior end of which carries 70 the roller 10. The valve head 8 is seated by the spring 11 having one end bearing on the stationary abutment 12, and its other end in engagement with the movable guide 13 secured proximate the exterior end of the stem 9. The valve chamber, and the valve are exteriorly detachable through the cylinder head. The oscillating or reciprocatory member 14 is provided with cam surfaces arranged for opening the valve 8 in a downward direction, and for permitting the valve 8 to be closed in its upward position under action of the spring 11. For securing these objects the member 14 is provided with the downwardly protruding cam portion 15 located to the right of the center thereof, with upwardly extending cam surfaces leading from both sides thereof, and said member 14 is mounted on the idle link 16 at one end thereof, the remaining end of the member 14 being pivoted to the arm 17 fixed to the oscillating shaft 18, constituting a parallel motion. The shaft 18 is oscillated by the timing shaft 20, suitably geared to or otherwise coupled to the engine shaft. The particular connections shown in Figs. 1 and 2 for oscillating the shaft 18 in synchronism with the engine shaft comprises the link or pitman 21 connected at one end by a crank 19 to the timing shaft 20, the other end be- 110

ing pivoted to the link 22, the remaining end of the link 22 being pivoted to the lever 23, adjusted by means of the adjustment nut 24 and link 31. The slide member 25 attached to the link or pitman 21 is adapted to reciprocate within the rocking fork or arm member 26, the latter being rigidly secured to the oscillating shaft 18. Thus, for any given adjustment of the adjusting means 24, the fork 26 will be oscillated upon the rotation of the timing shaft 20, thereby oscillating the shaft 18, arm 17 and cam member 14, controlling the valve 8. The fuel is likewise similarly controlled by the oscillating shaft 18 to which the cam 27 is fixed, the latter cooperating with the bell crank lever 28 for tripping the stem 29 of the needle valve 30. Fig. 2 indicates the fuel valve 30 in open position, whereas the valve 8, as shown in Fig. 1 corresponding in position of the parts to Fig. 2, is in closed position.

The relation of the timing shaft 20, oscillating shaft 18 and adjustable means is shown in simplified form in Fig. 3, the timing shaft 20 being disposed to the left, and adjustable lever 23 to the right. Upon drawing link 31 of the adjustable lever 23 downwardly, the link 22 will be moved upwardly relatively to the timing shaft, thereby moving the pivot 32 of oscillation of the pitman 21 upwardly; hence, for a complete rotation of the timing shaft 20, the arc of oscillation of the fork 26 will be decreased. The instants of opening of the fuel and scavenging valves will be practically unchanged; likewise, the instants of closing of said valves. Again, upon moving the arm 31 of the adjustable lever 23 upwardly, the pivot 32 of oscillation of the oscillating lever 21 will be moved downwardly thereby increasing the arc of oscillation of the fork member 26, the angle of oscillation of the shaft 18, and hence the extent of opening of the fuel and scavenging valves.

The schematic diagram shown in Fig. 4 indicates the arcs of movement and durations of the parts as arranged in Fig. 3. The line $o\ b$ may represent the time of opening of the air valve and also the time of closing of said valve. The line $o\ b'$ may represent the time of opening of the fuel valve and likewise the time of closing of said valve.

The lines $o\ c$ and $o\ c'$ represent the extreme positions of the fork, as for maximum oscillation and thereby maximum opening of the valves. Thus the duration of opening of the air valve is twice the angle $b\ o\ c$; likewise, the duration of opening of the fuel valve is twice the angle $b'\ o\ c'$. The dotted lines $o\ d$ and $o\ d'$ represent positions for lesser openings, in which cases the angle of duration of opening of the air valve is represented by twice the angle $b\ o\ d$, and the period of admission of fuel is represented

by twice the angle $b'\ o\ d'$. It will thus be seen that opening of a valve can be varied without changing its timing.

The provision of means for varying the extent of opening of a valve without changing its time of opening and closing in the cycle, is especially advantageous when applied to the Diesel type of engine herein shown. In this engine, as will be seen from Fig. 4, air is admitted at the line b' , on movement to the right toward d' or c' and cut off on the return movement at b' . The extent of opening is therefore governed by twice the distance from b' to the end of the oscillation. The fuel is likewise admitted at b during oscillatory movement to the left, and cut off at b during the oscillation to the right, irrespective of the amplitude of the oscillation from b , whether to d or c , or any other point. Regulation of the valve openings, to control the quantity of air and fuel, and which can be done simultaneously does not affect the combustion at different speeds, and powers. By this invention, the control and efficiency of the engine is very much improved.

In Fig. 5 is represented a modification of the connections between the oscillating lever 21 and the oscillating shaft 18, this figure showing the arm 33 fixed to the oscillating shaft 18, and a link 34 pivoted to the arm 33 and to the lever 21, the remaining parts being substantially as shown in Fig. 3.

The operation of the two-cycle engine represented in Figs. 1 and 2 will be clear from the above description. In the operation of this type of engine the piston will open the exhaust near the end of the down or working stroke, the scavenging air being admitted prior to the closing of the exhaust upon the returning or upward movement of the piston, the air which is retained in the cylinder after the exhaust is closed being compressed by the piston, the fuel being admitted into the cylinder when the piston is descending and fired at a desired instant, and the exhaust again opened by the piston at a point near its lowest position, these two cycles being repeated as described. It will be seen that the air valve in the engine described is opened at a different stage than the fuel valve.

It will be clear that the position of the adjustment arm 23 may be regulated by automatic means, as is indicated in Fig. 6, such as a centrifugal governor 35 connected to the arm 23 by link 36, lever 37 and arm 31, whereby at low speed the opening of the respective valves will be increased, and the same decreased at high speed. It will also be clear that my valve regulating arrangement is applicable to the control of but a single valve, and also to the simultaneous control of a plurality of valves in one or more cylinders.

While the invention is shown herein applied to a two-cycle engine both for controlling the fuel valve and an air valve, it is to be understood that the invention is not limited to this particular type of engine, but is applicable to valves of other types and different actuating connections from those herein shown. It will be understood, however, that the parallel motion valve actuating mechanism is peculiarly susceptible to regulation by my improved means, inasmuch as the cam can be made to strike the roller in opening and leave the roller in closing at the same time in the cycle, while the stroke of the cam while in contact with the roller and thereby the opening of the valve will be varied without affecting any of the other operations. Such a system of valve operation in connection with the four-cycle engine would be of particular advantage in controlling the power of the engine simply by the opening of the valves. It being seen that the power could be varied by varying the valve opening within wide limits.

Various modifications and changes in the mechanical arrangements herein shown may also be made without departing from the scope of the invention.

Having thus described my invention, I declare that what I claim as new and desire to secure by Letters Patent, is:

1. In a combustion engine, the combination with a valve, of means for operating said valve in predetermined relation to the cycle of the engine, and means for varying the extent of valve opening without affecting the times of opening and closing.

2. In a combustion engine, the combination with a puppet valve, of means for operating said valve in predetermined relation to the cycle of the engine, and means for varying the extent of valve opening without affecting the times of opening and closing.

3. In a combustion engine, the combination with an inlet valve, of means for operating said valve in predetermined relation to the cycle of the engine, and means for varying the extent of valve opening without affecting the times of opening and closing.

4. In a combustion engine, the combination with an inlet puppet valve, of means for operating said valve in predetermined relation to the cycle of the engine, and means for varying the extent of valve opening without affecting the times of opening and closing.

5. In a combustion engine, the combination with a valve, of a cam for operating said valve in predetermined relation to the cycle of the engine, and means for varying the throw of the cam to vary the valve opening without affecting the times of opening and closing.

6. In a combustion engine, the combination with a valve, of oscillatory cam means for opening and closing said valve at predetermined times, and means for varying the stroke of said oscillatory means to vary the extent of opening of said valve independent of said times.

7. In an engine, the combination with a valve, of an oscillatory cam member for opening and closing said valve at predetermined instants, and means for oscillating said cam member in synchronism with the rotation of the engine shaft, said last named means being adjustable to vary the stroke of oscillation from a fixed point of said cam member, without altering the times of opening and closing.

8. In an engine, the combination with a valve, of oscillatory means for opening and closing said valve at predetermined instants, and means for oscillating said means in synchronism with the shaft of the engine, said last named means being adjustable to vary the extent of oscillation of said oscillatory means without altering the times of opening and closing.

9. In an engine, the combination with a valve, of oscillatory means for opening and closing said valve at predetermined instants, and means for oscillating said means in synchronism with the shaft of the engine, said means comprising an adjustable part for varying the extent of oscillation of said means without altering the times of opening and closing.

10. In an engine, the combination with a valve, of an oscillatory device for opening and closing said valve at predetermined instants, means for oscillating said device, said means comprising a shaft driven by the engine, a pitman, and an adjustable connection between said pitman and said oscillatory device for varying the stroke of oscillation of said device from a fixed point without altering the times of opening and closing.

11. In an engine, the combination with a valve, of an oscillatory device for opening and closing said valve, at predetermined instants, means for oscillating said device, said means comprising a shaft driven by the engine, a pitman, and a connection between said pitman and said oscillatory device, and means for adjusting said pitman and said connection to vary the oscillation of said device to vary the extent of opening of said valve without altering the times of opening and closing.

12. In an engine, the combination with a valve, of actuating means comprising an oscillatory shaft, means oscillated by said shaft for moving said valve, and a pitman for oscillating said shaft, the connection between the pitman and shaft being intermediate its ends.

13. In an engine, the combination with a

- valve, of actuating means comprising an oscillatory shaft, means oscillated by said shaft for moving said valve, a pitman for oscillating said shaft, the connection between the pitman and shaft being intermediate its ends, and means for adjusting said pitman and connection to vary the oscillation of said device. 70
14. In an engine, the combination with a valve, of oscillatory means for actuating said valve comprising a shaft, a pitman rotatable at one end in synchronism with the engine shaft for oscillating said shaft, a pivotal support for the other end of said pitman, and an actuating connection between said pitman and said valve actuating shaft. 75
15. A two cycle engine comprising in combination a fuel inlet valve, a scavenging blast admission valve, single means for opening and closing said valves respectively at predetermined instants in the cycle of operation of the engine, and means for varying the extent of valve opening without altering the instants of opening and closing. 80
16. In an engine, the combination with a valve, of a crank and a pitman, the crank being driven in synchronism with the engine shaft, a cam driven by said pitman adapted to actuate said valve, and means for effecting relative adjustment between said pitman and said cam for variably controlling said valve. 85
17. In an engine, the combination of a valve having a reciprocating element, means for causing said element to reciprocate, said means comprising an oscillatory device adapted to engage said reciprocating element, a shaft carrying said oscillatory device, an arm having one end eccentrically mounted on the timing shaft of the engine, and means for pivotally supporting the other end of said arm. 90
18. In an engine, the combination of a valve having a reciprocating element, means for causing said element to reciprocate, said means comprising an oscillatory device adapted to engage said reciprocating element, a shaft carrying said oscillatory device, an arm having one end eccentrically mounted on the timing shaft of the engine, and adjustable means for pivotally supporting the other end of said arm. 95
19. In an engine, the combination of a valve and a cam for actuating said valve, a member rotated at one end in synchronism with the shaft of the engine, means for pivotally supporting the other end of said member, and an actuating connection between said member and said cam. 105
20. In an engine, the combination of a valve and a cam for actuating said valve, a pitman, means for rotating one end of said pitman in synchronism with the shaft of the engine, a link pivotally supporting the other 110
- end of said pitman, means for adjusting the position of said link relatively to the rotated end of said pitman, and an actuating connection between said pitman and said cam. 115
21. In a combustion engine, the combination with a valve, of an actuating cam, a rock shaft for operating said cam, an arm fixed to said rock shaft, and means for actuating said rock shaft in predetermined relation to the cycle of the engine, said means comprising an adjustable connection with said arm for varying the throw of said rock shaft without disturbing said predetermined relation. 120
22. In a combustion engine, the combination with a valve, of a cam, an oscillatory shaft for actuating said cam, a pitman for actuating said oscillatory shaft and connected to said oscillatory shaft, a rotatable connection between one end of said pitman and the engine shaft, and an adjustable fulcrum support for the pitman. 125
23. In a combustion engine, the combination with a valve, of a cam, a shaft for actuating said cam, a pitman for actuating said shaft and connected to said shaft, a rotatable connection between one end of said pitman and the engine shaft, and a pivotal support for the other end of the pitman. 130
24. In a combustion engine, the combination with a valve, of a cam, parallel links supporting said cam, a rock shaft for actuating said cam, and a pitman driven in synchronism with the engine shaft for actuating said rock shaft. 135
25. In a combustion engine, the combination with a puppet valve, of a cam, parallel links supporting said cam, a rock shaft for actuating said cam, and a pitman driven in synchronism with the engine shaft for actuating said rock shaft. 140
26. In a combustion engine, the combination with a valve, of a cam, parallel links supporting said cam, a rock shaft for actuating said cam, a pitman driven in synchronism with the engine shaft for actuating said rock shaft and an adjustable support for said pitman whereby to vary the movement of said cam to control the opening of the valve. 145
27. A combustion engine comprising in combination a fuel inlet valve, a scavenging blast admission valve, oscillatory means for opening said fuel valve at one portion of the oscillation and for opening the scavenging valve at another portion of the oscillation, and means for varying the amplitude of oscillation of said oscillatory means to vary the extent of opening of said valves without altering their respective times of opening and closing. 150
28. The combination with a cylinder and piston, of means for admitting air and fuel, oscillatory controlling means therefor, and 155

means for varying the amplitude of oscillation of said means.

29. A combustion engine comprising in combination with a fuel valve and a blast 5 scavenging valve, of an oscillatory controlling element for admitting fuel at one end of the oscillation and a scavenging blast at the other end of the oscillation, and means for varying the extent of oscillation of said 10 element.

30. In a combustion engine, the combina-

tion of a valve, a rock-shaft for operating said valve, an arm carried by said rock-shaft, a pitman slidably engaged by said arm, and means driven in synchronism with 15 the engine for actuating said pitman.

In testimony whereof I affix my signature, in presence of two witnesses.
